UNITED STATES PATENT OFFICE.

THOMAS H. BRADY, OF NEW BRITAIN, CONNECTICUT.

STORM-PROTECTOR FOR ELECTRIC LAMPS.

SPECIFICATION forming part of Letters Patent No. 390,440, dated October 2, 1888.

Application filed November 8, 1887. Serial No. 254,587. (No model.)

To all whom it may concern:

Be it known that I, THOMAS H. BRADY, a citizen of the United States, residing at New Britain, in the county of Hartford and State 5 of Connecticut, have invented certain new and useful Improvements in Storm-Protectors for Electric Lamps, of which the following is a specification.

My invention relates to improvements in 10 storm-protectors for electric lamps, and the objects of my improvement are to provide a storm-protector which can be readily attached to the lamp-frame, and to so construct and arrange the protector that it can be conveniently 15 opened and turned back out of the way where it will not interfere with trimming the lamp.

In the accompanying drawings, Figure 1 is 20 a front elevation of an electric lamp with my storm-protector attached. Fig. 2 is a side elevation of my protector and portions of the lamp, and Fig. 3 is an enlarged sectional view of a portion of the lamp-frame on line $x-x$ of Fig. 1, and a plan view of my protector attached to said frame and opened to furnish 25 access for trimming.

The lamp may be of any ordinary construction. I have illustrated it as provided with a frame, A, which extends downward to the base B on the outside of the globe C and 30 surmounted by a hood or roof, D. My storm-protector E is designed for use between the globe C and hood D for surrounding the carbon rod a, so as to protect the carbon from storms.

In order to furnish convenient access to the 35 carbons and carbon rod for trimming the lamp, I divide my storm-protector longitudinally into two or more parts, b b, (preferably only two,) and provide said parts near their meeting edges on one side with any suitable fastening device—as, for instance, the hooks c. The

side opposite the fastening devices I provide with hinges d d, which are extended laterally some distance from the body of the protector, so that when the divided protector is swung open, as shown in Fig. 3, the protector is wholly out of 45 the way of the trimmer and practically as free access is had to the carbons and carbon rod for trimming as if there were no protector on the lamp. The broken lines in Fig. 3 indicate the position of the protector when closed. 50

The hinges may be of any ordinary construction and secured in any ordinary manner to permit of the protector being opened, as shown in Fig. 3; but the best construction and manner of attachment known to me are illustrated 55 in the accompanying drawings, in which the hinges are formed upon clips f and attached to the frame by means of clamp-screws g. The frame A bows outward a little at the point for attaching the lower hinge, and therefore the 60 hinge-pintle is located farther inward on the clip, so that the pintles of the upper and lower hinges, when the clips are fastened in place, will be in alignment.

I claim as my invention— 65

1. The combination of a lamp-frame of an electric lamp with the storm-protector divided longitudinally and mounted upon hinges attached to said frame, substantially as described, and for the purpose specified. 70

2. In an electric lamp, the combination of the frame, the divided storm-protector having hinges d, and the clips f, bearing said hinges and adapted to be secured to said frame by clamp-screws, substantially as described, 75 and for the purpose specified.

THOMAS H. BRADY.
